UNITED STATES PATENT OFFICE.

CHARLES S. BIRD, OF WALPOLE, MASSACHUSETTS.

ROOFING FABRIC AND METHOD OF PREPARING SAME.

SPECIFICATION forming part of Letters Patent No. 690,348, dated December 31, 1901.

Application filed October 25, 1901. Serial No. 80,024. (No specimens.)

To all whom it may concern:

Be it known that I, CHARLES S. BIRD, of Walpole, Norfolk county, Massachusetts, have invented a certain new and useful Improvement 5 in Roofing Fabrics and the Method of Preparing the Same, of which the following is a specification.

It is my object, primarily, to produce a roofing fabric which will not be liable to "buckle" 10 after it has been applied to and secured in place on the roof or other part to be covered and protected by it.

When the ordinary roofing-paper is applied to a roof and secured in place by fastening 5 down its sides to the roof in the usual way, its exposure in that shape and under those conditions to the weather and to atmospheric influences will have the effect of causing it to buckle. This "buckling," so far as I have 20 been able to ascertain, is due to its absorption of moisture, whereby it is caused to expand. A slight percentage of moisture thus absorbed will cause buckles or ridges to appear all over the roof. If the weather be 25 such as to allow a larger percentage of moisture to get into the material, then the buckles and ridges will be even worse. The buckling is highly disadvantageous, not only in that it makes the roof-covering unsightly, but be- 30 cause it results in the formation of shallow cups or dishes, which will retain water, and the latter will finally soak through, with the result of rendering the roof leaky. Under my invention this liability of the roofing fabric 35 to buckle is removed, and by the mode of treatment employed by me to this end I find that the fabric itself is rendered stronger and less liable to tear.

To attain the result I have in view, I first 40 treat the fabric with waterproofing materials or compounds in any known or approved way for producing a waterproof roofing fabric, and I then subject the thus-prepared fabric to the action of water, either in the form of 45 liquid or vapor or steam, which will be taken up and absorbed by the prepared paper, with the effect of causing its expansion in the roll or prepared state and before its application for roofing purposes. The waterproofed fab- 50 ric thus treated with water will retain its moisture indefinitely under ordinary conditions. It will not buckle when applied to the

roof, because by the treatment to which it has been subjected it has been brought to and is maintained at what practically is its ex- 55 pansion limit under usual conditions, and it is stronger than waterproof paper which has not been water-treated. The percentage of water thus put into the paper may vary to a considerable extent, and I do not wish to be 60 understood as limiting myself to any special percentage. I may say, however, that from two to eight per cent. of the weight of the paper would be the practical limits of the 65 quantity of moisture to be put into water- proof paper of ordinary description, although even less than two per cent. would be a benefit, and in practice in the commercial manu- 70 facture of the article the quantity of moisture which I usually put into the paper is from 70 three to five per cent. of the weight of the latter.

The water can be introduced into the paper only after the latter has been waterproofed. If the water be first introduced, then the fab- 75 ric cannot afterward be properly saturated with the waterproofing liquor, and any at- tempt to do so will expel or drive off the water from the paper.

Various means of introducing the desired 80 percentage of water into the waterproof paper can be employed, and the water may be in- 85 troduced either before or after, or both be- fore and after, the waterproof paper has been put up in a roll without departure from my invention.

In the accompanying drawing, to which ref- 90 erence will now be made, I have represented, to a great extent diagrammatically, a simple form of apparatus which can be used in pro- 95 ducing one known kind of roofing fabric treat- ed in accordance with my invention, for which purpose in the present instance there is used a water-bath, through which the paper is drawn after it has been waterproofed and be- fore it has been put up in a roll.

In this apparatus, 1 is a roll of dry fabric to be treated. The web of fabric passes suc- 100 cessively into and through a pan 2 of hot oil or wax, thence over a drier or heater 3, thence between rolls 4, which take off some of the surplus waterproofing material, thence into a second hot pan 5, in which there is more hot oil or wax, and thence between pressure-

rolls 6, which remove all the surplus waterproofing material from the surface of the web. This completes the waterproofing operation, and heretofore the waterproofed fabric has been conducted directly from the rollers 6 to a stand, where it is wound into a completed roll 8, which is put up for the market in the usual way. Under my invention, however, the waterproofed fabric is conducted 10 into and through a water-bath 7, where it takes up the percentage of moisture requisite to effectuate the purposes of my invention, and from that bath it is wound into a roll, as at 8. This waterproofed water-treated roll of fabric 15 is then packed up for commercial purposes in the usual way.

In the case of other varieties of waterproofed roofing fabric—as, for example, roofing-paper saturated and coated with asphalt—20 the same mode of procedure is followed. The web of dry paper is conducted to and through the successive baths of hot asphaltum liquor, by which it is saturated and coated, and between the customary rollers for removing the 25 surplus and for aiding in the coating, and is then sprinkled with soapstone, as usual. Then after the waterproofing operation is completed the web is subjected to the action of water, as hereinbefore provided, in such a 30 way that it may take up and absorb the desired percentage of moisture.

Having described my invention and the best way now known to me of carrying the same

into effect, what I claim herein as new, and desire to secure by Letters Patent, is—

35

1. The improvement in the manufacture of waterproof roofing-paper which consists in first waterproofing the paper, and then subjecting the same to the action of water, to take up and retain a portion thereof, substantially as and for the purposes hereinbefore set forth.

40

2. The improvement in the manufacture of waterproof roofing-paper which consists in first waterproofing the paper, then subjecting the waterproofed paper to the action of water, to take up and retain a portion thereof, and then putting up the same in roll form, substantially as hereinbefore set forth.

45

3. The improvement in the manufacture of waterproof roofing-paper which consists in first waterproofing the paper, and then drawing the waterproofed paper through a bath of water, to take up and retain a portion thereof, substantially as hereinbefore set forth.

50

4. As a new article of manufacture, waterproofed roofing-paper, water-treated to retain a portion thereof, substantially as hereinbefore set forth.

55

In testimony whereof I have hereunto set my hand this 19th day of October, 1901.

CHARLES S. BIRD.
